UNITED STATES PATENT OFFICE

2,448,710

VERTICALLY ADJUSTABLE BOOKKEEPER'S TABLE

William F. Graeske, Clearwater, Fla.

Application February 16, 1945, Serial No. 578,283

1 Claim. (Cl. 311—39)

1

This invention relates to a table designed primarily for use by bookkeepers, the primary object of the invention being to provide a table having a top embodying a vertically movable book or ledger support, so constructed that the book or ledger supported thereon may be elevated or lowered to a position so that the open pages of the book or ledger, will lie in a plane with the surface of the table, for the comfort of the person using the book or ledger.

Another object of the invention is to provide a table top which may be rotated or moved towards and away from the person using the table, to locate the book or ledger supported thereon so that the person working with the book or ledger will have easy access thereto to the end that postings may be made and considered with facility.

With the foregoing and other objects in view which will appear as the description proceeds, the invention consists of certain novel details of construction and combination of parts hereinafter more fully described and pointed out in the claim, it being understood that changes may be made in the construction and arrangement of parts without departing from the spirit of the invention as claimed.

Referring to the drawings

Figure 1 is a plan view of a table constructed in accordance with the invention.

Figure 2 is a bottom view of the table top, portions of the table top being shown in section.

Figure 3 is a sectional view taken on line 3—3 of Fig. 1.

Figure 4 is a fragmental sectional view through the top.

Figure 5 is a sectional view taken on line 5—5 of Fig. 1.

Figure 6 is a sectional view taken on line 6—6 of Fig. 2.

Figure 7 is a sectional view taken on line 7—7 of Fig. 2.

Referring to the drawings in detail, the table embodies supporting legs 5 which are connected at their upper ends by means of the strips 6 that provide a support for the stationary top section 7. The stationary top section 7 is circular in formation and is provided with a track section 8 which cooperates with the track section 9 carried by the rotatable top section 10 so that the sections 8 and 9 act to hold the rotatable top section to the stationary section, and at the same time permit of rotary movement of the section 9 with respect to the stationary top 7.

Secured along opposite side edges of the rotatable top section 10, are track sections 11 which

2

cooperate with track sections 12 in securing the sliding top section 13 in position on the rotatable top section 10, so that the sliding top section 13 may be slid over the rotatable top section 10.

5 The sliding top section 13 is formed with a well in which the vertically movable book support 14 is mounted, the well being formed between the housings 15 that extend along the sides of the rotatable top section 10. The inner edges of the 10 housings 15 are arranged in parallel spaced relation with respect to each other and as shown, are disposed at acute angles in the horizontal plane, Fig. 1, with respect to the side edges of the table top.

15 Secured to the under surface of the vertically movable book support 14, are tracks 16 which embody spaced plates between which the arms 17 of the rods 18 and 19 operate. These tracks 16 are disposed in grooves formed in the bottom 20 of the book support 14, as clearly shown by Fig. 5 of the drawings.

On the free end of each arm 17, are rollers 20 which rollers move over the tracks 16 and while they operate to raise or lower the vertically movable book support 14, they also operate to secure the movable book support in its positions of vertical adjustment.

The rods 18 and 19 are mounted in bearings formed in the inner side walls of the housings 15, and one of the respective ends of the rods 18 and 19, is provided with a pinion 20. These pinions 20 contact with the pinions 21 formed at the ends of the shaft 22 that is provided with a gear 23, disposed intermediate the 35 ends of the shaft 22. The shaft 22 is mounted in bearings 24 that rise from the bottom of one of the housings 15.

The reference character 25 indicates a bearing that is supported within one of the housings 40 15, the bearing accommodating the shaft 26 on which the crank handle 27 is formed. On the inner end of the shaft 26 is a worm gear 28 that meshes with the gear 23 so that rotary movement of the shaft 26 will operate to move the rods 45 18 and 19 in opposite directions to the end that the arms 17 will swing towards or away from each other, according to the direction of rotation of the shaft 26. Should it be desired to elevate the book support so that the open pages of the book positioned thereon, will lie flush with the upper surface of the table, the crank handle 27 is operated to rotate the shaft 26 in the desired direction. The arms 17 will now swing towards each other and the wheels mounted at the outer ends of the arms 17 will move

over their track, raising the movable book support to the desired level.

When it is desired to lower the book, the handle will of course be rotated in the opposite direction.

From the foregoing it will be seen that due to the construction shown and described, a person working with a large account book or ledger, may position the book on the vertically movable book support and by operating the crank handle, elevate the book so that the person's arm will lie flat on the table top and book positioned on the table. Should it be desired to rotate the book, this may be done by merely moving the rotatable top section on its tracks. Should it be desired to move the book away from the operator or bring the book nearer to the operator to permit of posting or examination of the book at the upper or lower corners of the book, the book may be slid towards or away from the person using the book, by moving the rotatable table top backwardly or forwardly on the tracks 11 and 12.

What is claimed is:

A table of the class described comprising a table top having a well formed therein, a vertical movable book support operating within the well, tracks extending along the lower surface of the vertically movable book support, said tracks embodying elongated housings, one side of each housing comprising plates having their inner longitudinal edges spaced apart providing a clearance, spaced parallel operating rods extending across the bottom of the well, arms extending

laterally from the operating rods, said rods having upturned ends disposed between the longitudinal edges of the plates, rollers mounted on the free ends of the arms, said rollers operating within the elongated housings in contact with the flanges, gears secured to the ends of the rods, a transverse shaft mounted at the ends of the parallel operating rods, gears on the ends of the transverse shaft meshing with the gears 10 on the parallel rods operating the rods and arms as the transverse shaft is operated, a power shaft and gear operating the transverse shaft, and a crank handle formed integral with the power shaft by means of which the power shaft is operated, and the crank handle being disposed beyond the front edge of the table for easy operation.

WILLIAM F. GRAESKE.
